FLAGPOLE SUPPORT

Charles S. Bock, Chicago, Ill., assignor to Andrew Hoffman, Chicago, Ill.

Application November 4, 1937, Serial No. 172,844

5 Claims. (Cl. 116—173)

My invention relates to the supports usually employed in mounting flagpoles on buildings and other elevated structures, and main object is to provide a support which facilitates the disposal of the flagpole in a position leaning forward over the street or other space in front of the structure, so that the flag may be in full view. A well known form of flagpole support is found in the patent to Carr No. 1,132,303 dated March 16, 1915, and it is a further object of this invention to provide an improvement in supports of this type.

A further object of the invention is to utilize the conventional type of support, yet so improve the same that it may serve the additional purpose above referred to.

A still further object of the invention is to provide the invention as a replacement of the key employed in the standard flagpole support, so that the latter need not be altered or changed in any manner.

Another object of the invention is to design the novel improvement along the lines of extreme simplicity, economy and adaptability.

With the above object in view and any others which may suggest themselves from the description to follow, a better understanding of the invention may be had by reference to the accompanying drawing, in which—

Fig. 1 is a side view of the standard support with my improvement attached and with the flagpole in upright position.

Fig. 2 is a section on the line 2—2 of Fig. 1.

Fig. 3 is a view similar to Fig. 1, but showing the improved support with the flagpole in a leaning position; and

Fig. 4 is a perspective view of one of the units entering into the improvement.

In the conventional flagpole support, as depicted in the patent referred to, the flagpole is pivotally mounted in the support, so as to be both in a position to extend vertically and to be swung down in case the pole needs cleaning or other attention. As seen in Fig. 1, the support comprises a pair of laterally-spaced standards 10 having a spread toward the base and being there connected by spacer bolts 11.

A shaft 12 is horizontally journaled in the upper ends of the standards, the medial portion of this shaft having secured to it a double-jawed clamp 13 for the inner section 14 of the flagpole, bolts 14a serving to secure the jaws of the clamp.

The clamp 13 is formed with dual weights 15 at the bottom which is calculated to slightly overbalance the flagpole, so that ordinarily the

latter would be maintained in vertical position relative to the support. However, in case attention to the pole becomes necessary, the latter may be swung down by hand to lie close to the roof or top of the supporting structure.

When, as during a holiday or festive occasion, the flag is raised and the building or supporting structure is tall, it becomes difficult to notice or obtain a full view of the flag from the street below, so that the conventional flagpole support does not render a satisfactory service in such instance. The purpose would be served if the pole were tilted forward to extend partially over the street, but the manner in which the pole is fixed in the standard support does not permit such an adjustment. As seen in Fig. 2, the clamp 13 is transversely perforated with an oblong slot 13a which is adapted to be in alinement with a pair of similar slots 10a made in the standards 10. Ordinarily, when the flagpole is in the vertical position and the three slots are in alinement, a key is passed through them, one end of the key receiving a pin or bolt, while the other is slotted to receive a wedge which when driven down serves to gather the standards toward each other, and hold the support together more firmly. This fastening means is satisfactory as far as locking the pole in the vertical position is concerned and releasing the same when desired—by the removal of the key—to permit the pole to be swung down.

In the improved form, the support is used in its identical condition, except that the key is replaced by a frame composed of a pair of angle bars of identical construction. These bars are indicated at 19 and 20, and their end portions are indicated at 19a and 20a. When the flagpole is in upright position, the bar 19 may be inserted through the series of alined slots in the same manner as the key in the old form of support, and the bar 20 applied on the outside to complete the frame, as indicated in Figs. 1 and 2. In such event, the wedge is applied in the angle of the bar 19, as indicated at 21, the securing means at the opposite end of the bar being a bolt 22. A similar bolt 23 secures the opposite end of the bar 20 with the section 19a of the bar 19. As now constituted, the fastening does not differ functionally from the old one, the bar 20 merely serving as a surplus part.

However, in case it is desired to tilt the flagpole, the novel frame assumes a more extensive function. Thus, as seen in Fig. 3 the bar 19 is passed through the slot 13a of the flagpole clamp, 55

while the bar 20 is passed through the slots 10a of the standards 10, both bars being arranged as before to form a frame with overlapping ends.

It is now seen that the ends of the frame serve as brackets to fix the flagpole clamp in the inclined position when the bolts and wedge have been reapplied. Owing to the difference in the plane of the slot 13a from that of the slots 10a when the tilted fastening is made, the end portions 19a and 20a of the frame bars are given short bends 19b and 20b, so that they are adapted to the positions of the slots.

It will be seen from the above description that I have provided an appliance for the flagpole equipment which not only permits the flagpole to be given the upright and lowered positions, but also the forward leaning position in order that it may be easily seen from the street below. This position is of additional advantage in respect to the flag, as the latter spreads more fully when the pole is inclined, allowing a greater portion of its surface to be seen. Further, the appliance only adds one major part to the previous equipment and is altogether a simple assembly to handle, store or ship. Finally, it will be evident that the cost of producing the replacement is relatively low in comparison to that of the flagpole or its support, so that the appliance should be within the reach of any establishment desirous of employing a replacement having the advantages described.

I claim:

1. The combination with a support, a flagpole pivoted in poised position between the sides of said support, the flagpole and said sides having perforations therethrough which register when said flagpole is upright; of a quadrilateral frame having a side portion extending through said registered perforations when said flagpole is upright, a second side portion of said frame spanning adjacent sides of said flagpole and support, end portions of said frame connecting said side portions and overlying the sides of said support, said frame being composed of angle bars, and means to secure the angle bars together.

2. The structure of claim 1, those legs of said angle bars which are opposite the sides of the support terminating with bends effective to deflect the other side of the frame away from the plane of the latter.

3. In a flagpole and support therefor, said flagpole being pivoted to said support, said flagpole and support having perforations therethrough which are positioned to register when said flagpole is upright and to be out of registry when said flagpole is tilted; a frame having a pair of parallel side portions and at least one end portion detachably connecting said side portion together at one end thereof, one of said side portions being adapted to be passed through said registering perforations to maintain said flagpole upright, the other side portion being then adapted

ed to span adjacent sides of said flagpole and support, said first side portion being so formed as to be freely slidable in said perforations and readily removable therefrom whereby said flagpole can be tilted, and when in such tilted position one of said side portions being adapted to be extended through said perforation in said flagpole and the other side portion being adapted to be extended through said perforations in said support whereby to maintain said flagpole in said tilted position.

4. In a flagpole and support therefor, said flagpole being pivoted to said support, said flagpole and support having perforations therethrough which are positioned to register when said flagpole is upright and to be out of registry when said flagpole is tilted; a frame having a pair of parallel side portions and at least one end portion connecting said side portions together at one end thereof, one of said side portions being adapted to be passed through said registering perforations to maintain said flagpole upright, the other side portion being then adapted to span adjacent sides of said flagpole and support, said first side portion being so formed as to be freely slidable in said perforations and readily removable therefrom whereby said flagpole can be tilted, and when in such tilted position one of said side portions being adapted to be extended through said perforation in said flagpole and the other side portion being adapted to be extended through said perforations in said support whereby to maintain said flagpole in said tilted position, one of said side portions being offset to a higher plane than the other side portion.

5. In a flagpole and support therefor, said flagpole being pivoted to said support, said flagpole and support having perforations therethrough which are positioned to register when said flagpole is upright and to be out of registry when said flagpole is tilted; a frame having a pair of parallel side portions and at least one end portion connecting said side portions together at one end of said frame, one of said side portions being adapted to be passed through said registering perforations to maintain said flagpole upright, the other side portion being then adapted to span adjacent sides of said flagpole and support, said first side portion being so formed as to be freely slidable in said perforations and readily removable therefrom whereby said flagpole can be tilted, and when in such tilted position one of said side portions being adapted to be extended through said perforation in said flagpole and the other side portion being adapted to be extended through said perforations in said support whereby to maintain said flagpole in said tilted position, and a second end portion detachably connecting the side portions together at the other end of the frame.
